Inventor,

George A. Moore;

By *A. Blipham*,
Attorney.

UNITED STATES PATENT OFFICE.

GEORGE A. MOORE, OF MEDFORD, MASSACHUSETTS.

SOUND-BOX.

1,389,683.

Specification of Letters Patent. Patented Sept. 6, 1921.

Application filed September 23, 1919, Serial No. 326,419. Renewed September 25, 1920. Serial No. 412,893.

To all whom it may concern:

Be it known that I, GEORGE A. MOORE, a citizen of the United States, and a resident of Medford, in the county of Middlesex and Commonwealth of Massachusetts, have invented certain new and useful Improvements in Sound-Boxes, of which the following is a full, clear, and exact specification.

10 This invention has for its object the construction of improved means for pivotally supporting the needle arm of a talking machine sound box.

To this end, I clamp the needle arm to a 15 diaphragm supported at right angles to the plane of the resonator diaphragm, and provide means whereby the clamping means can be shifted in the plane of its diaphragm in order that the point of the needle arm's 20 attachment to the resonator diaphragm may be entirely neutral thereto, in other words, that it may have no tension thereon in either direction.

In the drawings forming part of this 25 specification, Figure 1 is a face view of a sound box embodying my improvements. Fig. 2 is a view of the same looking in the line of its stylus. Fig. 3 is a central sectional view of the same. Fig. 4 is a view 30 similar to that in Fig. 2 but with certain parts removed. Fig. 5 is a perspective view of a portion of the needle arm and its supporting diaphragm. Fig. 6 is a perspective view of the threaded annulus composing a 35 part of the clamping means for the supporting diaphragm. Fig. 7 is a sectional view of the same. Fig. 8 is a sectional view of the other member of the clamping means. Fig. 9 is a view of one of the cross arms 40 between which the supporting diaphragm is fastened. Fig. 10 is an edge view of the supporting diaphragm showing the cross arms of the needle arm attached thereto. Fig. 11 is a face view of the back plate of 45 the sound box.

The sound box case comprises an annular member 1 and a back plate 2 suitably attached thereto, as by screws 3, the back plate having a socket portion 4 for connection with the tone arm of the talking machine in a well known manner.

Rigid with the annular member 1 and preferably integral therewith, is a plate 5

as shown in Figs. 3 and 4. This plate has an opening 6 through it for the free passage 55 of the needle arm section 7, and also two slots 9 near its extremities.

The needle arm is in two sections 7 and 10, the section 10 containing the socket for the stylus 11, while the section 7 is attached 60 to the resonator diaphragm in a well known way. The cross arm 12, as shown in Figs. 5 and 9 is provided with an offset lug 13 rigidly connected with the needle arm section 7. These cross arms 12 and 14 have 65 their center lines located in the same plane with the diaphragm 15 and are attached to the opposite surfaces of the supporting diaphragm 16, preferably by rivets 17. The surface of each cross arm in contact 70 with the diaphragm 16 is narrowed down to substantially the diameter of the rivets 17, as shown in Figs. 9 and 10, and its ends are further narrowed to points, as shown in Fig. 9.

75 For supporting the diaphragm 16, an externally threaded ring 20 is provided, and an internally threaded ring 21, the latter being constructed to be screwed on over the former. Each ring is provided with an annular lip 22 constructed to clamp the diaphragm 16 between them when the rings are screwed together. The ring 20 is formed with a diametrical recess 23 of a width to snugly receive the plate 5, and is 80 attached thereto by screws 24 passing through the slots 9 into the ring. Small pins 25 projecting from the ring 20 into holes 28 in the diaphragm 16 serve to 85 keep the latter accurately in place for maintaining the parallelism between the cross arms 12, 14 and the diaphragm 15.

90 In the manufacture of this sound box, the outer surface of the plate 5 is made exactly at right angles to the plane of the annulus 95 1. The needle arm sections 7, 10 are attached to the diaphragm 16, and the latter clamped between the lips of the rings 20, 21. Then the attaching end 27 of the arm section 7 is accurately ground to lie at right 100 angles to the diaphragm 16, or, at least, to the inner surface of the recess 23. Now, the needle section 7 having been introduced through the opening 6, and the recess 23 pressed into engagement with the plate 5, 105 the rings 20, 21 are slid up or down there-

on until the end 27 is just touching the diaphragm 15 but not pressing it. The screws 24 are then tightened up until the rings are firmly fixed in place, and the point 27 is 5 attached to the diaphragm in a well known manner.

By thus having the needle arm supported without initial strain upon the resonator diaphragm 15, every vibration communicated to the stylus 11, no matter how delicate, will be transmitted to the resonator diaphragm. 10

The narrowing of the contact surfaces of the cross arms 12, 14, as shown in Fig. 9, 15 is for the purpose of increasing the pivotal sensitiveness of the needle arm. It is, of course, necessary to have the cross arms of sufficient width not to be weakened by the rivet holes, but by narrowing the contact 20 faces and widening the remainder of the cross arms, the desired narrowness is obtained without diminishing the strength. This narrowness is further extended at points extending beyond the rivets, as shown in Fig. 25 9, for the purpose of diminishing the possibility of any vibration or yielding laterally in the same plane with the diaphragm 15, so that there can be no vibration of the needle arm except in a plane at right angles 30 to this diaphragm, thus further increasing the perfection of tone communicated to the sound box.

As shown in Figs. 3 and 11, I prefer to have the back plate 2 large enough in diameter to reach nearly to the extreme periphery of the annulus 1 and to form it with a notch 26 fitting the plate 5. This coaction of the notch 26 and plate 5 renders the act of positioning the back plate in the annulus much 40 easier and quicker than it would otherwise be, inasmuch as soon as the back plate has had its notch engage the plate 5 and is introduced within its seat in the annulus, the screw holes for the screws 3 will be found 45 accurately alined and the screws can be inserted immediately.

What I claim is:

1. A sound box comprising a case, a resonator diaphragm supported by said case, 50 a pivotal diaphragm supported substantially at right angles to the plane of the resonator diaphragm and with its center in the plane of the same, and a needle arm supported by the pivotal diaphragm and attached to the resonator diaphragm.

2. A sound box comprising an annulus, a resonator diaphragm supported thereby, a plate rigid with the annulus and projecting at right angles to the plane of the diaphragm and in opposite directions from the annulus, a pivotal diaphragm, an annular member supporting the pivotal diaphragm and slidable on said plate, means adjustably binding the annular member to said plate, 65 and a needle arm supported by the pivotal

diaphragm and attached to the resonator diaphragm, said plate having an opening for the passage of the needle arm.

3. A sound box comprising an annulus, a resonator diaphragm supported thereby, a 70 plate rigid with the annulus and extending at right angles to the plane of the diaphragm in opposite directions from the annulus, a pivotal diaphragm, an annular member supporting the pivotal diaphragm 75 and slidable on said plate, said plate having slots through it, screws passing through said slots into engagement with said member, and a needle arm supported by the pivotal diaphragm and attached to the resonator 80 diaphragm.

4. A sound box comprising an annulus, a resonator diaphragm supported thereby, a 85 plate rigid with the annulus and projecting at right angles to the plane of the diaphragm, a pair of rings supported by said plate, one having an internally threaded portion and the other a threaded periphery screwing into said portion, a pivotal diaphragm clamped between the rings, and a needle arm supported by the pivotal diaphragm and attached to the resonator diaphragm. 90

5. A sound box comprising a resonator diaphragm, a pivotal diaphragm, two rings 95 clamping the edges of the latter between them, means movably supporting said rings, and a needle arm attached at one end to the resonator diaphragm and supported at an intermediate point by the pivotal diaphragm. 100

6. A sound box comprising an annulus, a resonator diaphragm supported thereby, a plate rigid with the annulus and extending at right angles to the plane of the diaphragm, an externally threaded ring supported by 105 said plate, an internally threaded ring coacting with the former ring, a pivotal diaphragm clamped between the two rings, means attaching the externally threaded ring to said plate, and a needle arm supported by the pivotal diaphragm and attached to the resonator diaphragm. 110

7. A sound box comprising an annulus, a resonator diaphragm supported thereby, a parallel-sided plate held by the annulus at 115 right angles to said diaphragm and having a longitudinally extended slot near each end, an externally threaded ring slidably fitting said plate, screws passing through said slots into engagement with said ring, 120 an internally threaded ring coacting with the former ring, a pivotal diaphragm clamped between said rings, and a needle arm supported by said pivotal diaphragm and attached to said resonator diaphragm. 125

8. A sound box comprising an annulus, a resonator diaphragm supported thereby, an externally threaded ring, an internally threaded ring coacting with the former ring and opposing the first-named ring, a pivotal 130

diaphragm clamped between said rings, means connecting said rings and annulus, and a needle arm supported by the pivotal diaphragm and attached to the resonator 5 diaphragm.

9. A sound box comprising a resonator diaphragm, a pivotal diaphragm supported near its edges at right angles to the plane of the resonator diaphragm, with its center in 10 the plane of the latter, and a needle arm attached to the resonator diaphragm and to the pivotal diaphragm, the needle arm being formed with an offset for enabling it to avoid contact with the box and to present 15 the needle in substantially the same plane with the resonator diaphragm.

10. A sound box comprising a resonator diaphragm, a pivotal diaphragm, means supporting the pivotal diaphragm, two narrow 20 extended cross arms clamping the pivotal diaphragm between them with their center at the center of the latter diaphragm and lying in a plane parallel with the resonator diaphragm, and a needle arm attached at 25 one end to the latter diaphragm, and intermediately supported by said cross arms.

11. A sound box comprising an annulus, a resonator diaphragm supported thereby, 30 a pivotal diaphragm, means supporting the latter near its edges connected with said annulus, a needle arm terminally connected with the resonator diaphragm and having a transversely disposed cross arm, a second 35 cross arm adapted to carry the stylus, and means clamping said cross arms tightly together with the pivotal diaphragm between, the surfaces of the cross arms in contact with the pivotal diaphragm being quite narrow 40 in comparison with the portions of the pivotal diaphragm beside them.

12. A sound box comprising an annulus, a resonator diaphragm supported thereby, a plate held by said annulus at right angles 45 to the diaphragm having an opening

through it, a pivotal diaphragm supported by said plate substantially parallel with it but spaced therefrom, and a needle arm in two sections each having a cross arm, means clamping the cross arms together at opposite 50 surfaces of the pivotal plate, one of the sections having a socket for the reception of the stylus, the other section being attached to the resonator diaphragm, and passing through said opening, one of said cross arms 55 having a projection therefrom substantially parallel with the pivotal diaphragm but spaced therefrom and connecting this cross arm with the last-mentioned needle arm section. 60

13. A sound box comprising a resonator diaphragm, a pivotal diaphragm, a needle arm attached to the resonator diaphragm, united means supporting said diaphragms, and means attaching said needle arm to the 65 pivotal diaphragm consisting of two cross arms lying in the same plane with the resonator diaphragm with the pivotal diaphragm between, and rivets or the like passing through said cross arms and clamping them and the latter diaphragm tightly together, the surface of each cross arm contacting with the pivotal diaphragm being narrowed to substantially the diameter of 70 said rivets. 75

14. A sound box comprising a resonator diaphragm, a pivotal diaphragm, united means supporting said diaphragms at right angles to each other, the center of the pivotal diaphragm being in the same plane with the 80 resonator diaphragm, a needle arm attached to the resonator diaphragm and supported by the pivotal diaphragm, and a stylus carried by the needle arm with its axis in the same plane with the resonator diaphragm. 85

In testimony that I claim the foregoing invention, I have hereunto set my hand this 15th day of September, 1919.

GEORGE A. MOORE.
